UNITED STATES PATENT OFFICE.

FRANK M. JOSLIN, OF AMSTERDAM, NEW YORK, ASSIGNOR TO INMAN MANUFACTURING COMPANY, INC., OF AMSTERDAM, NEW YORK, A CORPORATION OF NEW YORK.

FOLDING MECHANISM.

1,400,292.

Specification of Letters Patent. Patented Dec. 13, 1921.

Application filed March 29, 1920. Serial No. 369,491.

To all whom it may concern:

Be it known that I, FRANK M. JOSLIN, a citizen of the United States, and residing at Amsterdam, Montgomery county, New York 5 State, have invented certain new and useful Improvements in Folding Mechanism, of which the following is a specification.

This invention relates to a machine for making boxes such as match boxes and the 10 like and it is concerned particularly with a mechanism adapted to fold the edges of the material in the formation of such boxes.

The invention contemplates certain detailed improvements over the construction 15 shown in my prior Patent No. 1,356,771 issued October 26, 1920.

More specifically the present invention aims to simplify and improve the construction of my said prior patent by providing 20 a plunger and die mechanism in which both of the plates for folding the edges of the box are carried upon a single member of the plunger and in which the die member is provided with means for guiding the movable 25 die plate during its movements and with improved means for mounting the spring for actuating the movable die plate.

The invention is illustrated in one form in the accompanying drawings in which:

30 Figure 1 is a front elevation of the plunger and the die, certain parts being shown in section, the members of the plunger being shown in their separated position;

35 Fig. 2 is also a view in elevation taken at right angles to that shown in Fig. 1, parts of the die being omitted;

40 Fig. 3 is a sectional view on the line 3—3 of Fig. 5 illustrating the manner of mounting the folding plates and showing the upper plunger member in a position somewhat in advance of the position illustrated in Fig. 1;

45 Fig. 4 is a sectional view similar to that of Fig. 3, but showing the plunger members in the die and showing the folding plates lying in a recess in one of said members;

Fig. 5 is a transverse sectional view on the line 5—5 of Fig. 1; and

50 Fig. 6 is a perspective view of a box such as the machine is intended to produce illustrating at one end the material folded into final position and at the other in a partially folded position.

Referring to the drawings in detail, 10 represents a die which is suitably secured in 55 a fixed part of the machine. Slidably mounted in this die is a plate 11 secured to the upper end of a supporting rod 16 and provided with a guide rod 12 passing through an opening in the bottom of the die, this 60 guide rod serving to guide the movements of the plate 11 in the die. A cylindrical stop member 13 is rigidly mounted in a depression 10^a in the bottom of the die being secured to the die in any suitable manner as 65 by screw threads 14. A coiled spring 15 surrounds said cylindrical member 13, and extends into the depression 10^a of the die, said spring being intended to bear against the under face of the plate 11 and hold the same 70 in a position in advance of the cylindrical member 13 and adjacent the outer end of the die. The cylindrical member 13 is provided with a bore through which the rod 16 passes, this rod being provided with a 75 head 17 which constitutes means for limiting the extent to which the plate 11 can be moved by the coiled spring 15.

A plunger is provided for coöperating with the die heretofore described, this 80 plunger consisting of two members 18 and 19 which are movable relative to each other and which for convenience may be termed respectively the body member and contact member. The contact member 19 consists 85 of a plate to which is secured a stem 20, this stem extending into suitable openings in the body member 18. Mounted on the stem 20 is a collar 21 to which the folding plates 22, 22 are pivotally secured. At the point of 90 pivotal connection between said collar and said plates springs 23 are mounted, these springs being so arranged as to hold the folding plates yieldingly in the path of movement of the member 18 or against the 95 lower portion of such member. The body member 18 is provided with a suitable recess 24 in which the folding plates are adapted to lie when the two members of the plunger are brought together. Means are provided 100 for yieldingly holding the members 18 and 19 in separated position, such means comprising a coiled spring 25 surrounding the stem 20 of the member 19 and bearing at one end against a fixed part of the member 18, an abutment 26 being secured to said

stem 20 against which the other end of said coiled spring 25 is adapted to bear, the abutment 26 extending at each end into a groove or guideway 26^a formed in the member 18. 5 It is to be understood that the plunger here- tofore described is attached to suitable mechanism of a box machine which is adapted to give said plunger a reciprocating motion toward and from the die.

10 To briefly outline the operation of the mechanism it will be understood that the plate 11 of the die 10 is normally held by the coiled spring 15 in a position near the outer end of the die and that the material 15 which is intended to be folded by the mechanism of the present invention lies in a suitable position above said plate. Upon movement of the plunger toward the die the member 19 of the plunger contacts with the 20 material which serves to clamp the same between said member and the plate 11. As the plunger continues to move toward the die the coiled spring 15 is depressed until the plate 11 contacts with the cylindrical stop member 13 which prevents further movement 25 of said plate into the die. The guide rod 12 serves to maintain the plate 11 in proper position in the die and to guide the same as it is moved relative to the die. The wall of 30 the recess in the bottom of the die serves to maintain the spring 15 in proper position about the stop member 13 and by reason of the depression in the bottom of the die the distance between the plate 11 and the bottom 35 of the die is reduced which construction results in rendering the action of the guide rod 12 more effective. The movement of the plunger thus far described results in shaping the material into the form shown at A in 40 Fig. 1. When the movement of the member 19 of the plunger together with its stem 20 has been arrested, as described, the member 18 continues to move toward the die, and during such movement this member contacts 45 with the folding plates 22, 22, which causes movement of said plates about their pivotal connection on the stem 20. As said plates are caused to move about their pivot point they contact with the projecting edges of the 50 material and fold the same into the position shown at B in Fig. 3. Upon further movement of the member 18 toward the member 19 the plates 22, 22 enter the recess 24 of the member 18 and as said member continues its 55 movement into the die and toward the member 19 it comes in contact with the partially folded edges of the material and completely folds the same into the position shown in Fig. 4. Upon the reverse movement of the 60 plunger the member 18 is first withdrawn from the die which permits the folding plates 22, 22, to resume the position shown in Fig. 1 and further movement serves to withdraw the plate 19 from the die and permit the 65 sliding plate 11 to be moved by the spring

15 into its position adjacent the opening of the die.

What I claim as my invention and desire to secure by Letters Patent is:

1. In a machine of the kind described, a 70 plunger comprising a body member and a contact member, a stem secured to the contact member and slidably engaging the body member, means for yieldingly holding said contact member in advance of said body 75 member, said body member having a recess at its lower end through which said stem extends, a pair of folding plates pivotally connected to said stem on opposite sides thereof and normally held in yielding en- 80 gagement with opposite sides of the front face of said body member when said contact member occupies its normal position in front of the body member, said plates being shaped to enter the recess of said body member upon relative movement of said body member and contact member.

2. In a machine of the kind described, a 90 plunger comprising a body member and a contact member, a stem secured to the contact member and slidably engaging the body member, means for yieldingly holding said contact member in advance of the body member, said body member having a recess at its lower end through which said stem extends, 95 a collar secured to said stem, a pair of folding plates pivotally connected to said collar on opposite sides of said stem and extending outwardly beyond opposite sides of said body member, means for yieldingly holding said 100 plates in engagement with the front portion of said body member when said contact member occupies its normal position in front of the body member, said plates being shaped to enter the recess of said body member upon 105 movement of said body member and contact member toward each other, and means for preventing rotation of said stem in said body member.

3. In a machine of the kind described, a 110 plunger comprising a body member and a contact member, a stem secured to the contact member and slidably engaging the body member, means for yieldingly holding said contact member in advance of said body 115 member, said body member having a recess at its lower end through which said stem extends, a pair of folding plates pivotally connected to said stem on opposite sides thereof and normally held in yielding en- 120 gagement with opposite sides of the front face of the said body member when said contact member occupies its normal position in front of the body member, said plates being shaped to enter the recess of said body member upon relative movement of said body member and contact member, a die into which 125 said plunger is adapted to project, a sliding plate arranged in said die, resilient means acting on said plate and normally holding 130

the same at the top of said die, a guide rod secured to said plate and extending downwardly through the bottom of said die, stop means in said die for limiting the movement 5 of said sliding plate into the die, the arrangement being such that when said plunger enters said die said sliding plate is

forced against said stop by said contact member and said folding plates are caused to move about their pivot point by the further 10 advance of said body member toward the die.

In testimony whereof I affix my signature.

FRANK M. JOSLIN.
